5 Claims. (Cl. 250—40)

1

This invention relates to frequency determining circuit arrangements of the kind comprising a number of inductances and condensers together forming a resonant circuit having only one resonant frequency and which is tunable over a band of frequencies $F_t - F_0$, this band of frequencies being divided into "m" major sub-bands of substantially equal width and each major sub-band being divided into "n" substantially equal minor increments ΔF , switching means being provided whereby the minor elements corresponding to any desired multiple of ΔF up to a $n\Delta F$ can be selected while at the same time selecting any one of the major elements corresponding to the "m" major bands. Preferably the incremental minor elements are chosen to give exactly equal frequency increments ΔF when associated with one particular major element, whereas each of the remaining major elements is so adjusted that at two frequencies lying within the frequency band corresponding to that major, the frequency increment is an exact multiple of ΔF as described and claimed in our co-pending application No. 764,885, now issued as Patent No. 2,496,177, January 31, 1950.

According to the present invention, at least one of the interval switches and preferably both the major interval switch and the minor interval switch are duplicated or provided with an additional selector arm. In the case of the major interval switch the two arms are spaced by a predetermined major interval ΔF_m whereas in the case of the minor interval switch the two arms are spaced by a predetermined minor interval ΔF_n . An auxiliary switch may be provided whereby either combination of switch arms is utilised, giving a choice of two resonant frequencies differing by the fixed amount $\Delta F_m + \Delta F_n$. Such a switch arrangement enables the circuit to be used as the sole frequency determining element of a combined transmitter-receiver, where it is desired to change the frequency by a constant interval on changing from "transmit" to "receive" and vice versa. For this purpose the auxiliary switch can be coupled with the change-over switch.

For a better understanding of the invention, reference is made to the following detailed description thereof to be read in connection with the accompanying drawing, wherein:

Fig. 1 is a schematic diagram of one preferred embodiment of the invention, and

Fig. 2 is a schematic diagram of another preferred embodiment of the invention.

The system illustrated in Fig. 1 contains two

2

switches, a minor interval switch K_1 with two switch arms K_{11} and K_{12} set at a predetermined spacing corresponding to a minor interval ΔF_n , and a major interval switch K_2 with two switch arms K_{21} and K_{22} set at a predetermined spacing corresponding to a major interval ΔF_m .

To give m major intervals for each of the arms K_{21} and K_{22} , the number of major elements $LmCo$ required is $m' = ma$ where a is an integer determined by ΔF_m . Arms K_{21} and K_{22} are arranged to engage successively the fixed contacts 1, 2, 3, etc., of switch K_2 , each contact being connected to a major resonator element Lm_1Co_1 , Lm_2Co_2 , etc. Similarly to give n minor intervals for each of the arms K_{11} and K_{12} , the number of minor elements Cn required in addition to Cn_0 (the effective capacity in the zero position of the arm K_{11}) is $n' = n + b$ where b is an integer determined by ΔF_n . Thus arms K_{11} and K_{12} are arranged to engage successively contacts 0, 1, 2, etc. of switch K_1 , each contact being connected to a minor element Cn_0 , Cn_1 , Cn_2 , etc. The numbers of major and minor elements are related to the frequency range $F_t - F_0$ and the basic minor increment ΔF by the relationship

$$m'n' = \frac{F_t + \Delta F_m + \Delta F_n - F_0}{\Delta F}$$

30 The arms K_{11} and K_{21} are connected in common via lead 20 to one terminal of a change over switch K_3 , and the arms K_{12} and K_{22} are connected in common via lead 21 to the other terminal, so that operation of the switch K_3 changes the frequency by a predetermined amount $\Delta F_m + \Delta F_n$.

Another circuit arrangement according to the present invention is shown diagrammatically in Fig. 2 of the accompanying drawings. This arrangement which is adapted more particularly for use in a transmitter-receiver, differs from the circuit shown in Fig. 1 primarily in that the major interval switch K_2 has three switch arms K_{21} , K_{22} and K_{23} set at intervals corresponding to two major intervals, the minor interval switch K_1 has only one switch arm, whereas the change over switch has three arms K_{31} , K_{32} and K_{33} coupled so as to be adjusted simultaneously to one of the three positions S , R_1 and R_2 , corresponding to the "send" position and first and second "receive" positions.

The major elements each consist of the parallel connection of inductance and capacity as shown for the major position 10. The inductance Lm_{10} is connected in parallel with a main condenser Co_{10} and a trimmer condenser Co'_{10} .

to enable the major interval ΔF_m to be pre-set to the required degree of accuracy. If desired, provision may also be made for trimming to inductance Lm_{10} . The minor elements each consist of a capacity C_{n1} , C_{n2} etc., with provision for trimming as, for example, by means of a trimmer C_t connected in parallel with a minor element. With one selected major it is possible to trim all the minors to give zero frequency deviation from the nominal interval ΔF_n , and to trim each major so that the frequency deviation is zero at two positions of the minor switch, in accordance with the invention claimed in U. S. Patent No. 2,496,177.

A major element selected by one of the arms K_{21} , K_{22} and K_{23} in accordance with the setting of the change-over switch K_3 is connected in parallel with the minor element selected by the switch K_1 to determine the frequency. The major intervals may for example be 100 kc./s. and the minor intervals 5 kc./s. The auxiliary condensers C_{21} , C_{22} , C_{23} enable the change in frequency on switching over from K_{21} to K_{22} or from K_{22} to K_{23} to be different from the frequency difference determined by the major intervals ΔF_m . Thus, with major intervals of 100 kc./sec. and the spacing K_{21} — K_{22} and K_{22} — K_{23} equal to two major intervals as shown, the frequency change on switching K_3 from S to R , or from R_1 to R_2 can be made equal to 230 kc./sec. instead of 200 kc./sec.

To enable finer tuning than the intervals ΔF_n determined by the minor elements, viz. 5 kc./sec. in the numerical example quoted, a variable condenser C_1 is provided which is constructed to have a click position at its centre point at which it is normally set. For fine tuning within the 5 kc./sec. steps, this condenser C_1 is adjusted in the appropriate sense out of its central position. The condenser C_1 may be furnished with a calibrated scale giving a direct reading of the adjustment effected in kc./sec.

A trimmer condenser C_2 enables the values of the major and minor elements to be adjusted for correct frequencies with a nominal capacity and later trimmed to the same capacity when in the circuit to be used.

An adjustable condenser C_3 which is in circuit only when the switch K_3 is in one of the "receive" positions R_1 or R_2 , enables the receiver to be aligned to another transmitter which is slightly off tune.

The appropriate values for the components can be ascertained in the manner described in the said U. S. Patent No. 2,496,177. Similarly, the variants in circuit arrangement indicated in that application may be utilised in the present case.

We claim:

1. A frequency-determining adjustable resonant system comprising a series of resonant circuits each tuned to a predetermined frequency, the frequencies of said circuits being uniformly spaced, a first multi-contact switch having a movable arm for successively engaging each of said contacts, each of said contacts in said first switch being connected to one end of a respective circuit, the other ends of said circuits being interconnected, a series of reactance elements having mutually different values, a second multi-contact switch having a movable arm for successively engaging each of said contacts, each of said contacts in said second switch being connected to one end of a respective element, the other ends of said elements being interconnected, one of said first and second switches further in-

cluding an auxiliary movable arm coupled for simultaneous movement with the movable arm thereof and spaced a predetermined number of contacts from said movable arm, a pair of output terminals the first of which is connected to both the interconnection of said circuits and the interconnection of said elements, and means to connect selectively the second of said terminals in one position to the movable arms of both said first and second switches and in another position to the auxiliary movable arm of said one of said switches.

2. A frequency-determining adjustable resonant system comprising a series of resonant circuits each tuned to a predetermined frequency, the frequencies of said circuits being uniformly spaced, a first multi-contact switch having a movable arm for successively engaging each of said contacts and an auxiliary movable arm coupled for simultaneous movement with the movable arm and spaced a predetermined number of contacts therefrom, each of said contacts in said first switch being connected to one end of a respective circuit, the other ends of said circuits being interconnected, a series of reactance elements having mutually different values, a second multi-contact switch having a movable arm for successively engaging each of said contacts and an auxiliary movable arm coupled for simultaneous movement with the movable arm and spaced a predetermined number of contacts therefrom, each of said contacts in said second switch being connected to one end of a respective element, the other ends of said elements being interconnected, the movable arms of said first and second switches being interconnected, the auxiliary arms of said first and second switches being interconnected, a pair of output terminals the first of which is connected to both the interconnection of said circuits and the interconnection of said elements, and means to connect selectively the second of said terminals in one position to the interconnection of the movable arms and in another position to the interconnection of the auxiliary movable arms.

3. A frequency-determining adjustable resonant system comprising a series of resonant circuits each tuned to a predetermined frequency, the frequencies of said circuits being uniformly spaced, a first multi-contact switch having a movable arm for successively engaging each of said contacts and an auxiliary movable arm coupled for simultaneous movement with the movable arm and spaced a predetermined number of contacts therefrom, each of said contacts in said first switch being connected to one end of a respective circuit, the other ends of said circuits being interconnected, a series of reactance elements having respective values effecting uniform changes in the resonant frequency of one of said circuits when successively connected thereto, a second multi-contact switch having a movable arm for successively engaging each of said contacts and an auxiliary movable arm coupled for simultaneous movement with the movable arm and spaced a predetermined number of contacts therefrom, each of said contacts in said second switch being connected to one end of a respective element, the other ends of said elements being interconnected, the movable arms of said first and second switches being interconnected, the auxiliary arms of said first and second switches being interconnected, a pair of output terminals the first of which is connected to both the interconnection of said circuits and the interconnection of said elements.

tion of said elements, and a selector switch arranged to connect in one position the second of said terminals to the interconnection of said movable arms and in another position to connect the said second of said terminals to the interconnection of said auxiliary movable arms.

4. A frequency-determining adjustable resonant system comprising a series of resonant circuits each tuned to a predetermined frequency, the frequencies of said circuits being uniformly spaced, a first multi-contact switch having first, second and third movable arms for successively engaging each of said contacts, said arms being coupled for simultaneous movement and being spaced a predetermined number of contacts from each other, each of said contacts in said first switch being connected to one end of a respective circuit, the other ends of said circuits being interconnected, a series of reactance elements having mutually different values, a second multi-contact switch having a movable arm for successively engaging each of said contacts, each of said contacts in said second switch being connected to one end of a respective element, the other ends of said elements being interconnected, a pair of output terminals the first of which is connected to both the interconnection of said circuits and the interconnection of said elements and the second of which is connected to the movable arm of said second switch, and means to connect the second of said terminals selectively to said first, second and third movable arms of said first switch.

5. A frequency-determining adjustable resonant system comprising a series of resonant circuits each tuned to a predetermined frequency,

the frequencies of said circuits being uniformly spaced, a first multi-contact switch having first, second and third movable arms for successively engaging each of said contacts, said arms being coupled for simultaneous movement and being spaced a predetermined number of contacts from each other, each of said contacts in said first switch being connected to one end of a respective circuit, the other ends of said circuits being interconnected, a series of reactance elements having mutually different values, a second multi-contact switch having a movable arm for successively engaging each of said contacts, each of said contacts in said second switch being connected to one end of a respective element, the other ends of said elements being interconnected, a pair of output terminals the first of which is connected to both the interconnection of said circuits and the interconnection of said elements and the second of which is connected to the movable arm of said second switch, means to connect the second of said terminals selectively to said first, second and third movable arms of said first switch, and a variable reactance element having a click position at its center point connected across said pairs of terminals.
